UNITED STATES PATENT OFFICE.

ALFRED COTTON, OF ST. LOUIS, MISSOURI, ASSIGNOR TO HEINE BOILER COMPANY, OF ST. LOUIS, MISSOURI, A CORPORATION OF MISSOURI.

SUPERHEATER BOILER.

Application filed April 29, 1920. Serial No. 377,539.

To all whom it may concern:

Be it known that I, ALFRED COTTON, a citizen of the United States, residing at St. Louis, Missouri, have invented a certain new and useful Improvement in Superheater Boilers, of which the following is a full, clear, and exact description, such as will enable others skilled in the art to which it appertains to make and use the same.

10 This invention relates to water tube boilers of the cross drum, upright tube type.

One object of my present invention is to provide a superheater boiler of the general type referred to which is of such design 15 that a greater degree of superheat can be obtained than is possible with superheater boilers of the kind now in use, thereby increasing the efficiency of the boiler when it is equipped with a superheater of conventional size, or permitting a small superheater to be used without reducing the efficiency of the boiler.

Another object is to provide a superheater boiler which is so constructed that 25 the amount of superheat can be accurately regulated. Other objects and desirable features of my invention will be hereinafter pointed out.

To this end I have devised a boiler which 30 comprises a number of cross drums and a number of banks of upright water tubes connected with said cross drums, a superheater arranged preferably in the space between the first and second tube banks, and a 35 shield or partition arranged near the front side of the first tube bank in such a manner that the long flame or hydrocarbon gases from the front of the fire will travel the full height of the combustion chamber before crossing over the first tube bank and the short flame gases from the back of the fire will escape from the combustion chamber under the lower edge of said shield and then divide or split up into two streams, 40 one of said streams entering the superheater chamber and the other stream flowing upwardly among the tubes of the first bank.

The Figure of the drawing is a vertical 50 sectional view of a superheater boiler constructed in accordance with my invention.

Referring to the drawings, 1 designates the first bank of water tubes, 2 the second or middle bank, 3 the third or rear bank, 4 55 the mud drum to which the feed water is

supplied; 5, 6 and 7 the front, middle and rear steam-and-water drums that communicate with the upper ends of the tubes of the banks 1, 2 and 3, respectively, 8 the water circulators and 9 the steam circulators 60 that connect the front drum 5 with the middle drum 6, and 10 and 11 the water and steam circulators, respectively, that connect the middle drum 6 with the rear drum 7, the steam outlet 12 preferably leading 65 from the rear drum 7. A shield or partition A is arranged at the front side of the first tube bank 1, so as to cause the long flame gases, indicated by the arrows x, rising from the front of the fire, to travel 70 slowly upwardly through the combustion chamber B and then flow rearwardly over the upper edge of said shield A across the tubes of the first bank 1, and the short flame gases, indicated by the arrows marked 75 y, rising from the back of the fire, to escape from the combustion chamber under the lower edge of the partition A and follow a different path than said long flame gases. The shield or partition A produces the same 80 results as the shield or partition of the boiler described in my pending application for patent Serial No. 373,250, filed April 12, 1920, and can be constructed in various ways without departing from the spirit of 85 my invention.

A superheater C is arranged in a chamber between the first and second tube banks in such a manner that part of the short flame gases from the back of the fire will 90 enter the lower end of said superheater chamber, flow upwardly through same over the superheater C and the escape from the upper end of said chamber, as indicated by the arrows in the drawing. Said superheater chamber is formed by a baffle D arranged at the rear side of the first tube bank 1 and a baffle E arranged at the front side of the second tube bank 2, the baffle D having its upper and lower edges spaced away from the front steam-and-water drum 5 and from the mud drum 4, so as to form passageways through which the gases can travel, and the baffle E extending upwardly from the mud drum 4 and terminating at a point below the middle steam-and-water drum 6. The baffle D is provided with a rearwardly-projecting shelf 13 that forms the top side or wall of the superheater chamber, and a controlling

valve or damper 14 is arranged adjacent the discharge opening at the upper end of the superheater chamber through which the gases escape. A horizontally-disposed baffle 5 15 is preferably arranged in the superheater chamber between the inlet and outlet of said chamber so as to direct the gases over the superheater, as indicated by the arrows in the drawing. A baffle E, which is arranged at the rear side of the second tube bank 2, extends downwardly from the middle drum 6 to a point in proximity to the mud drum 4 so as to cause the gases to flow downwardly among the tubes of the 10 second bank and then upwardly among the tubes of the third bank to a discharge opening 16 at the upper end of the boiler, 15

When the boiler is in operation the long flame gases *x* from the front of the fire travel slowly upwardly through the combustion chamber and then flow rearwardly over the upper edge of the shield A across the tubes of the front bank 1. The short flame gases *y* from the back of the fire escape from 20 the combustion chamber under the lower edge of the shield A and enter the front tube bank 1 at the lower end of said bank. These short flame gases are again split up 25 into two streams by the baffle D that forms the front wall of the superheater chamber, part of said gases flowing upwardly among the tubes of the first bank 1 and the remainder passing into the superheater chamber under the bottom edge of the baffle D. Due 30 to the fact that the short flame gases from the back of the fire require only a short time and small space to complete combustion, combustion of the gases used to heat the superheater is complete before said gases 35 enter the superheater chamber. Moreover, as the gases which pass through the superheater chamber have made only a small contact with the heating surface of the boiler since they pass straight across the lower end 40 portion of the first tube bank 1, said gases are much hotter than gases which have made a full pass over the first tube bank of the boiler before impinging upon the superheater. Consequently, the superheater of 45 my boiler will give a much higher degree of superheat than the superheater of a cross drum, upright tube superheater boiler of the kind now in general use. This is advantageous, in that the efficiency of the boiler 50 is materially increased when it is equipped with a superheater of conventional size, and it makes it possible to materially reduce the size of the superheater without decreasing the efficiency of the boiler. In the superheater boilers of the kind now in general use 55 the superheater is generally arranged in parallel relation with one of the tube banks, thus making it difficult to control the amount of superheat. In my improved boiler the 60 amount of gases passing over the super- 65

heater can be accurately controlled, and consequently, the amount of superheat may be regulated either automatically or by hand.

In order to attain sufficient superheat with controlled gas flow, it means that the desired 70 amount of superheat must be possible of attainment with less than the maximum gas flow. If, with a given superheater (such as is usually attached to a Stirling boiler) all the gases are necessary to give sufficient 75 superheat, then with the same size of superheater with a diminished gas flow or controlled gas flow, the gases must be hotter than usual. If the superheater is heated merely by a portion of the mixed hot gases 80 from the combustion chamber, or by gases that have passed over only a small amount of heating surface of the boiler, two difficulties, due to incomplete combustion, are experienced. One is, that secondary 85 combustion is liable to take place in the superheater chamber, thus varying the amount of superheat attained and making it almost impossible to control the superheat. The other is that soot is deposited on the superheater 90 elements, reducing their efficiency and making accurate control of the temperature of the superheated steam more difficult.

By constructing the boiler so that the shortest of the short flame gases only enter 95 the superheater chamber, combustion is quite complete before the gases enter the superheater chamber, and consequently, delayed combustion inside of the superheater chamber is avoided. As the gases which are 100 used to heat the superheater are derived from that part of the fire where there is little or no hydrocarbon, deposits of soot on the superheater elements is avoided.

I am aware of the fact that it is old to arrange a superheater between the front and middle banks of tubes of a Stirling boiler, but my improved boiler is distinguished from the usual Stirling superheater boiler, in that it is so constructed that the superheater is heated by a controlled flow of gases 110 taken from the extreme rear end of the fire.

Having thus described my invention, what I claim as new and desire to secure by Letters Patent is:

1. A boiler of the semi-vertical tube type provided with a front bank of water tubes, a superheater arranged behind said front bank, means for causing the long flame gases from the front of the fire to travel upwardly through the combustion chamber before coming in contact with the main body of tubes of the front bank, and means for causing the short flame gases from the back of the fire to separate into two streams, one of which streams flows upwardly over the superheater and the other upwardly among the tubes of the front bank.

2. A boiler of the semi-vertical water tube type having three transverse steam-and-water

- drums each connected by a bank of tubes to a transverse mud drum, a superheater in the space between the first and second banks of tubes, means for causing the gases from the front of the fire to travel upwardly through the combustion chamber before coming in contact with the main body of tubes of the first bank, and means for causing the gases from the back of the fire to separate into two streams, one of which streams flows upwardly among the main body of tubes of the first bank and the other upwardly over the superheater.
3. A water tube boiler of the vertical tube, cross drum type provided with a plurality of banks of tubes, a superheater chamber between the first and second tube banks provided at its lower end with an inlet and at its upper end with an outlet, a superheater arranged in said chamber, a partition arranged at the front side of the first bank of tubes in such a manner that the long flame gases from the front of the fire will travel upwardly through the combustion chamber and then rearwardly across the upper portion of the first tube bank and the short flame gases from the back of the fire will enter the lower end of the first tube bank, the inlet of the superheater chamber being located adjacent the lower end of same so that a portion of the short flame gases will pass into the superheater chamber through said inlet.
5. A water tube boiler of the upright tube type provided with three banks of upright water tubes, a mud drum communicating with the lower ends of said tube banks, cross drums communicating with the upper ends of said tube banks, a partition arranged at the front side of the first tube bank with its upper and lower edges spaced away from the front drum and mud drum, respectively, a baffle arranged at the rear side of said first tube bank with its upper and lower edges spaced away from the front drum and mud drum, respectively, for the purpose described, a superheater arranged at the rear side of said baffle, and baffles arranged at the front and rear sides of the second tube bank in such a manner that the gases will flow downwardly among the tubes of the second bank and then upwardly among the tubes of the third bank.

ALFRED COTTON.
